ELECTRICAL MEASURING APPARATUS

Benjamin C. Lansdale, San Francisco, Calif., assignor to Echlin Manufacturing Company, San Francisco, Calif., a corporation of California

Application January 30, 1939, Serial No. 253,516

7 Claims. (Cl. 177-311)

This invention relates to improvements in electrical measuring apparatus and, more particularly, to apparatus and methods for measuring or indicating the relative duration of the closure period in an electrical circuit which is intermittently opened and closed.

The present invention may be employed in any instance where it is desired to determine, in electrical circuits which are intermittently opened and closed at a frequency above a certain minimum, the fractional ratio of the time that the circuit is closed with respect to the time of completed cycle of operation of the circuit, i. e. the time between two successive closures of the switch. The invention has found application in the internal combustion motor art as a "cam angle meter," the purpose and function of which will be now outlined.

In order to secure the most efficient operation of internal combustion motor ignition systems, it is necessary to adjust the breaker contacts of the distributor to remain closed a time in a predetermined ratio to the time in which the contacts remain separated. The longer the contacts remain closed, the more nearly the time of primary current flow approaches the time required to charge the reactors in the circuit and for the potential to rise to the maximum predetermined by the values of the reactances. The greater the current flow in the primary at a given motor speed, the higher the induced potential in the secondary and the hotter the spark delivered. However, the current flow should not be high enough to cause undue temperature rise in the coil or excessive sparking at the breaker points. It is with this attainment of the optimum relative time for contact closure that the present invention is particularly concerned.

The automotive art has generally adopted the term "cam angle" to express the relative duration of the closure period of the contacts, and this term will be adhered to throughout this specification. "Cam angle" is specifically defined as the number of degrees through which the distributor cam rotates while the breaker contacts remain closed.

Heretofore it has been the practice to measure the cam angle geometrically by means of a protractor. This operation was carried out either by attaching mechanical measuring means to the distributor shaft, or by removing the distributor from the motor and setting it into a special test fixture. Either operation was time consuming and, moreover, often inaccurate, since the effective cam angle may be different in ac-

tual operation. Slightly loose or worn bushings supporting the distributor cam shaft, or slight play in the plate upon which the contacts are mounted, may cause, and frequently do cause, a change in the effective cam angle, when the distributor cam shaft rotates at normal operating speeds from the cam angle which would be measured when the shaft is rotated very slowly.

In an attempt to overcome these disadvantages, several types of cam angle meters have been developed for measuring the cam angle with the distributor cam shaft rotating at substantially normal speed. Broadly, these meters operate on a common principle. If direct current voltage is impressed across a circuit consisting of a battery, the breaker contacts, and a voltmeter, all connected in series, and the contacts successively opened and closed at relatively high speed, the voltmeter will give a reading proportional to the fraction of time the contacts remain closed with respect to the time of a completed cycle. In other words, the voltmeter will indicate the mean voltage impressed across it, since the rapidity of the intermittent current impulses precludes the voltmeter responding to them individually.

These types of measuring apparatus required that the breaker contacts be placed out of service while the measurements were being taken, since the normal high frequency potential oscillations in the ignition circuit would otherwise interfere with the proper functioning of the circuit. One type of system provided an auxiliary make-and-break means to replace temporarily the breaker contacts in the distributor. This made no provision for timing the spark in proper relation to the mechanical operation of the motor. This caused erratic operation of the motor while the cam angle was being measured and possible damage to certain parts of the motor. Another system involved running the motor at high speed, opening the ignition circuit, and then connecting the metering circuit to breaker contacts to measure the cam angle while the motor was still turning over under its own momentum. This was disadvantageous since the readings had to be made hurriedly before the motor came to a stop. Furthermore, racing of an internal combustion motor with no imposed load is damaging to the motor.

The present invention renders it possible to measure the cam angle while the ignition system is simultaneously functioning in its normal manner.

55 Among the objects of the invention is to filter

the high frequency oscillations in the ignition circuit from the metering circuit so as to enable the measuring of a substantially direct current potential.

Another object is to avoid the use of electronic relays or vacuum tubes which are undesirable because of their limited life and the inability of the average mechanic to diagnose the cause of trouble in the event of their failure.

Another object is to provide an apparatus which may be easily calibrated to compensate for differences in the potential of the batteries in the ignition circuits containing the breaker contacts whose cam angles are to be measured.

Another object is to provide an apparatus which can be readily connected to the ignition system to be tested.

Another object is to avoid imposing an appreciable current drain on the ignition circuit by the metering circuit.

Another object is to provide an apparatus substantially fool-proof in design and relatively simple in operation so that it may be successfully used by the relatively unskilled.

Other objects and advantages appear as this description progresses.

In this specification and the accompanying drawings, the invention is disclosed in its preferred form. It is to be understood, however, that it is not limited to this form, but may be embodied in other forms without departing from the spirit of the invention as defined in the claims following the description.

The present invention is particularly shown and described in connection with its use as a cam angle meter. It, however, will be understood by those skilled in the electrical arts that it may be utilized in other instances where it is desired to determine the duration of the closure period of an electrical circuit relative to the time of the completed cycle of operation where opening and closing of the circuit is recurring at a frequency above a certain minimum. Such a relative period of closure of an electrical circuit can be measured under the present invention even should it be subject to discontinuous variations, in which case the linear average period of closure at any given moment will be indicated. In the case that the relative duration of the closure period continuously varies with time, the reading of the meter will similarly vary with time.

In the one sheet of drawings:

Fig. 1 is a schematic wiring diagram of a simple form of measuring apparatus constructed in accordance with this invention and connected to a circuit which is intermittently opened and closed.

Fig. 2 is a similar diagram of a preferred form of the invention functioning as a cam angle meter connected to the conventional ignition system of an internal combustion motor.

Fig. 3 is a similar diagram of modified form of the invention wherein the metering circuit is energized by a source of substantially constant potential.

Fig. 4 is a graph of the potential in a circuit shunted across an impedance in the primary circuit of a conventional ignition system plotted against time and showing the typical transient oscillations occurring when the ignition circuit is opened.

Fig. 5 is a similar graph illustrating the effect of interposing a choke coil in the shunt circuit.

Fig. 6 is a similar graph showing the effect of

an interposed choke coil and one-way impedance in the shunt circuit.

Fig. 7 is a similar graph of the potential in the shunt measuring circuit of Fig. 2.

In Fig. 1, the circuit whose period of closure relative to the completed cycle of closing and opening is to be measured, comprises in series a source of electric potential, such as the battery 1, an impedance 2, and the switch 3 which is opened and closed at a frequency above a certain minimum. The measuring circuit is shunted across the impedance 2 and includes the meter 4, the variable resistance 5, and the double throw switch 6. One contact of the switch 6 is connected back to the battery 1 through the ground 7, short-circuiting the switch 3. The meter 4 is an ammeter but is preferably graduated in terms of percent and has a maximum reading of one hundred percent. The switch 6 is thrown so as to short-circuit the switch 3 through the ground 7. Current then flows from the battery 1, through the meter 4, the variable resistance 5, and the ground 7, back to the battery 1. The variable resistance 5 is then adjusted so as to bring the index of the voltmeter 4 over the graduation marked "100%." The apparatus is now ready for use.

This preliminary calibration by means of the variable resistance 5 provides a standardized maximum voltage for the meter 4 and thus enables accurate functioning of the apparatus despite differing potentials in the circuits to be tested. It is desirable that the actuating means for intermittently opening and closing the switch 3 be in normal operation during the calibration of the meter 4. The meter 4 then will be calibrated against the voltage of the current source 1 under normal operating conditions which may be slightly lower than for open circuit conditions due to the current drain through the resistance 2 and the switch 3.

In making the desired measurement, the switch 6 is thrown to complete the metering shunt circuit through the contact 8. Current then flows through the meter 4, the resistance 5, the switch 6, the switch 3, and back to the current source 1. If the switch 3 be opened and closed at a frequency above a certain minimum, say ten cycles per second, the meter 4 will be unable to respond to the individual potential waves impressed thereacross but will give a reading proportional to the average voltage. This average voltage will be in substantially linear proportion to the fraction of the time that the switch 3 remains closed with respect to the time of its total cycle of operation, thus causing the meter 4 to give a reading indicating this time fraction.

In the embodiment of the invention, above described, the reactances in the circuit are required to be relatively low and the meter 4 sufficiently damped to be unaffected by the oscillations attendant upon the opening of the switch 3. Where the metering apparatus is to be used in conjunction with circuits having high reactance values therein and consequent marked oscillations associated with the intermittent current flow as in the conventional ignition system of internal combustion motors, the form of the invention shown in Fig. 2 is preferred.

The type of conventional ignition system illustrated in Fig. 2 comprises an input circuit including in series, a current source such as the usual storage battery 10, with one of its poles grounded at 11 and its opposite pole connected to the primary 12 of the coil C by the conductor 13. The

input circuit is completed by the conductor 14 connected to the opposite side of the primary 12 and leading through the breaker contacts 15 to the ground at 16. These contacts are located in the usual distributor and are intermittently opened and closed by the cam 17 in synchronism with the operation of the motor. The capacitor 18, in the form of a fixed condenser, is interposed between the conductor 14 and the ground 19 and coacts with the inductive reactor 12 to set up high frequency oscillations in the circuit each time contact at 15 is broken.

The output of the ignition system includes the secondary 20 of the coil C which may be connected to the conductor 13 or otherwise grounded. The usual rotor 21 of the distributor is connected to the opposite terminal of the secondary 20 and completes the circuit through each of the plurality of grounded spark plugs, such as 22, successively. The oscillations in the input circuit set up between the inductive reactor 12 and the capacitor 18, upon the breaking of the contacts 15, induces a high potential in the secondary 20 to generate a spark at 22. This mode of operation is well known to those skilled in the art and is herein described only to point out the conditions under which the present metering system is adapted to operate.

The metering shunt circuit shown in Fig. 2 is arranged to block out completely the transient oscillations in the ignition system and to admit to the metering instrument only the intermittent uniform flow of unidirectional current corresponding to the intermittent closing of the contacts 15 and unaffected by the characteristic behavior of the reactors 12 and 18. The shunt circuit includes, in series, the conductor 23 connectable to the battery terminal of the primary 12 of the ignition coil C, the choke coil 24, the conductor 25, the copper oxide type rectifier element 26, the voltmeter 27, the variable resistor 28, the conductor 29, and the double throw switch 30. One pole of the switch 30 is grounded at 31 while the other pole is connectable through the conductor 32 to the terminal of the primary 12 of the ignition coil C leading to the breaker contacts 15. The copper oxide rectifier element 33 is connected between the conductors 25 and 29 providing a path parallel to the rectifier element 26, the meter 27, and the resistor 28. The reversing switch 34 is interposed in the conductors 23 and 29, and enables reversal of the connection of these conductors to the ignition system where the present apparatus is used in conjunction with an ignition system wherein the polarity of the battery 10 is reversed.

The meter 27 may be a voltmeter or a milliammeter requiring 20 milliamperes for full scale deflection but is graduated either in terms of percent or in degrees. One hundred percent is the maximum reading of the meter in case of its being graduated in percent, or sixty degrees in the case of a meter graduated in degrees and to be used in conjunction with six or twelve cylinder motors. For use in conjunction with four or eight cylinder motors, the meter, if graduated in degrees, would have a maximum reading of ninety or forty-five degrees, respectively. The meter may carry all four scales to permit readings in percent or degrees regardless of the number of cylinders of the motor whose cam angle is being measured.

The choke coil 24 has 300 turns of No. 20 wire layer wound on a form approximately $\frac{1}{2}$ inch in diameter and is of the air core type, and the var-

iable resistor 28 has a maximum resistance of 700 ohms. The copper oxide rectifier elements 26 and 33 each have a direct flow resistance of 8 to 10 ohms and a reverse flow resistance of 7500 ohms under a potential of 2.0 volts. The values recited are preferred because they have been found to be most suitable where the present apparatus is to be employed in its principal use in conjunction with the conventional ignition system. It will be obvious, however, to those skilled in the art, that these values may be considerably varied in this and other practical applications of the invention.

The rectifier element 26 is arranged to permit the flow of positive current in the direction of the arrow through the ammeter 27 while imposing a high resistance on the flow of current in the reverse direction. The rectifier element 33 provides a low resistance bypass path for the flow of current in the reverse direction through the shunt circuit thus decreasing the potential of the reverse current across the rectifier element 26 and thus increasing the effectiveness of the rectifier element 26 in blocking out this current from the meter 27. The high resistance of the rectifier 26 to current in the normal direction minimizes the loss of this current through the bypass path.

Figs. 4 to 7 diagrammatically illustrate the effect of the choke coil 24 and the rectifier elements 26 and 33 in filtering out transient oscillations from the metering shunt circuit. Fig. 4 is a graph of the potential E in a substantially non-reactive circuit shunted across the terminals of the primary 12 of an ignition coil, plotted against the time t showing the typical oscillations occurring when the contacts 15 are broken.

Fig. 5 shows the damping effect of the choke coil 24 in reducing these oscillations in a shunt circuit wherein the coil 24 is the sole reactance. It will be noted that, while the oscillations are considerably diminished by the action of the choke coil, they are still marked. It is unnecessary that the choke coil accomplish more than superficial damping of the oscillations, reducing them to the extent the fluctuation is of negative potential values only, the amplitude of the oscillations being sufficiently damped so that they do not cross the line of zero voltage and thus impress transient positive potentials across the shunt circuit. This requirement being complied with, the unidirectional resistors 26 and 33 will suffice to block out completely the residual oscillations from the metering shunt.

Fig. 6 illustrates the effect of the choke coil 24 plus the rectifier element 26, in series, in a shunt circuit across the primary 12. It has been found that the rectifier element 26 substantially completely suppresses the damped oscillations passed by the choke coil 24. These oscillations being of negative potential throughout, obviously would be greatly diminished by the high resistance of the opposed rectifier element 26. Their substantially complete diminution is possibly due to a capacitance effect in the rectifier unit. The single wave of negative potential across the shunt circuit arises from the fact that the rectifier element 26 presents only a finite resistance to current in the reverse direction.

In the shunt circuit of Fig. 2, this single wave of negative potential is completely diverted from the meter 27 through the low resistance path provided by the rectifier element 33. The intermittent potential impressed across the meter 27

then assumes a uniform positive value as indicated in Fig. 7.

The procedure in using the apparatus shown in Fig. 2 is substantially the same as for the use of the simplified apparatus of Fig. 1. The conductors 23 and 32 are connected to the terminals of the primary 12 of the ignition coil C and the motor started. The switch 30 is thrown to complete a circuit through the ground 31. Current then flows from the battery 10, the conductors 13 and 23, the choke coil 24, the conductor 25, the rectifier element 26, the meter 27, the resistor 28, the conductor 29, the switch 30, and back to the battery through the grounds 31 and 11. The potential impressed across the meter 27 is then calibrated against the voltage of the particular battery 10 by adjusting the potentiometric variable resistance 28 until the index of the meter 27 is brought opposite the dial graduation marked "100%" or other maximum graduation should the meter be graduated in other units, such as degrees.

After the metering apparatus is thus calibrated, the switch 30 is reversed to complete the shunt circuit through the conductors 32 and 14, and the breaker points 15 to the ground 16. The voltage impressed across the meter 27 and its consequent reading will then be linearly proportional to the time fraction that the breaker points are closed relative to their complete cycle of operations as has been herein before described in connection with the simplified embodiment of the invention illustrated in Fig. 1. As the action of the pointer of the meter is somewhat slow relatively to the speed of opening and closing of the breaker points at any speed at which it is practical to operate a motor, the pointer will give a constant reading without substantial oscillations.

In the modified apparatus illustrated in Fig. 3, the metering circuit is provided with its own source of current and is arranged so that there is substantially no interchange of potential between the ignition system and the metering subcircuit. This permits the subcircuit to be substantially permanently calibrated with respect to its own source of potential so that the measuring means will give accurate readings when used in conjunction with ignition systems having batteries of varying voltage, without the necessity for further calibration to compensate for such varying voltages in the individual ignition systems.

In Fig. 3 similar parts of the conventional ignition system are indicated by reference numerals similar to those in Fig. 2. Parts of the modified metering apparatus corresponding to parts in Fig. 2 are designated by corresponding reference numerals with addition of an *x* character.

The modified apparatus comprises, connected in series, the conductor 23*x* adapted to be connected to the battery terminal of the breaker contacts 15, two poles of the reversing switch 34*x*, the battery 35, the choke coil 24*x*, the rectifier element 26*x*, the conductor 25*x*, the milliammeter 27*x*, the adjustable resistor 28*x*, and the conductor 29*x* leading to the ground 16 through the other two poles of the reversing switch 34*x*.

The rectifier element 33*x* is shunted between the conductor 29*x* and the conductor 25*x* which is located between the rectifier 26*x* and the milliammeter 27*x*.

The battery is arranged so that its potential is counter to that of the battery 10 at the point A as indicated by the arrows. Should the battery 10 have its positive pole grounded as is the case in certain ignition systems, the polarity of the

battery 35 can be reversed by means of the reversing switch 34*x*. The voltage of the battery 35 is such that the potential it impresses on the conductors 23*x* and 29*x* when the breaker points 15 are separated is somewhat less than the counterelectromotive force impressed by the battery 10. The battery 35 is consequently unable to produce a reverse current flow in the ignition system when the breaker points 15 are opened. Current under the higher potential of the battery 10 is substantially blocked from the metering subcircuit by the high resistance of the opposed rectifier element 26*x*.

The operation of the modified apparatus is analogous to the operation of the form shown in Fig. 2. When the contacts 15 are closed, current flows from the battery 35 through the subcircuit path comprising the conductor 23*x*, the breaker points 15, the conductor 29*x*, the milliammeter 27*x*, the resistor 28*x*, the rectifier element 26*x*, and the choke coil 24*x*. As before, the meter 27*x* will respond to the mean current flowing, and indicates the fraction of the time the points 15 remain closed relative to the time of their completed cycle of operation. The combined action of the choke coil 24*x* and the rectifier elements 26*x* and 33*x* filters the high frequency oscillations of the ignition primary from the metering subcircuit in the manner hereinbefore discussed in connection with Fig. 2.

Since the maximum deflection of the meter 27*x* is dependent only upon the voltage of the battery 35, and not upon the battery 10 in an ignition system, the modified apparatus need be calibrated only during its manufacture and at rare intervals to compensate for any deterioration of the battery 35. Closing the switch 30*x* connects the conductors 23*x* and 29*x*, completing a continuous circuit through the meter 27*x*. The potentiometric resistor 28*x* is then adjusted until the meter 27*x* shows full scale deflection.

While the use of copper oxide rectifier units at 26 and 33 is greatly preferred for practical reasons, it is obvious that other types of rectifiers, such as various types of electrolytic cells, electronic relays, etc., could be substituted without departing from the spirit of this invention as defined in the following claims.

To simplify the terminology of the following claims, current flowing in the direction corresponding to the normal flow when the breaker points 15 are closed is expressed as flowing in the positive direction, which current in the reverse direction is described as flowing in the negative direction.

Having thus described this invention, what I claim and desire to secure by Letters Patent is:

1. An apparatus for measuring the time ratio of the periods of closure relative to the periods of completed cycles in a main circuit which is intermittently closed and opened at a frequency above a certain minimum to impress a positive potential across an impedance therein, said circuit having inductive and capacitive reactances therein whereby negative potential oscillations of high frequency across said impedance are set up each time said circuit is opened, comprising a metering circuit having its input shunted across said impedance, energy measuring means in said shunt circuit, and rectifying means in said shunt circuit arranged to block the imposition of a negative potential on said energy measuring means.

2. An apparatus for measuring the time ratio of the periods of completed cycles in a main cir-

cuit intermittently closed and opened at a frequency above a certain minimum to impress a potential across an impedance therein, said circuit having inductive and capacitive reactances therein whereby incidental potential oscillations of high frequency across said impedance are set up each time said circuit is opened, comprising a metering circuit having its input shunted across said impedance, energy measuring means in said shunt circuit, a reactance in said shunt circuit having an inductance such that said incidental oscillations will be damped in said shunt circuit, and rectifier means arranged to permit the passage of current through said measuring means only when said main circuit is closed.

3. An apparatus for measuring the time ratio of the periods of closure relative to the periods of completed cycles in a main circuit intermittently closed and opened at a frequency above a certain minimum to impress a positive potential across an impedance therein, said circuit having inductive and capacitive reactances therein whereby high frequency oscillations of potential across said impedance are set up each time said circuit is opened; comprising a metering circuit having its input shunted across said impedance, energy measuring means in said shunt circuit; a choke coil interposed in said shunt circuit adapted to damp said incidental high frequency oscillations therein; a rectifier element in series with said measuring means and arranged to present relatively high resistance to the flow of current in the negative direction therethrough; and a bypass shunted across said measuring means and said rectifier element and adapted to provide a relatively low resistance path to the flow of current in said negative direction; and a rectifier element in said bypass adapted to present relatively high resistance to the flow of current in the positive direction.

4. A cam angle meter for measuring the period of closure relative to the completed cycle of the breaker contacts in an internal combustion motor ignition system, comprising a shunt circuit having as its input the primary of the ignition coil in said system, current measuring means in said shunt circuit; a choke coil interposed in said shunt circuit adapted to damp incidental high frequency oscillations, a rectifier element of the copper oxide type in series with said measuring means and arranged to present relatively high resistance to the flow of current in a negative direction; a bypass shunted across said

measuring means and adapted to provide a relatively low resistance path to the flow of current in the negative direction, a rectifier unit in said bypass adapted to present a relatively high resistance to the flow of current in the positive direction, an adjustable resistor adapted to control the potential impressed across said measuring means, and means for connecting said shunt circuit directly to the source of current in said ignition system.

5. Means for measuring the dwell of the periodic breaker means of an ignition system having a source and an induction coil primary in series with said means, comprising a voltmeter connected in parallel circuit with said primary and a rectifier in series with the voltmeter in said parallel circuit, the rectifier having such a polarity that said source when applied to said primary is also applied to said voltmeter through minimum resistance, but when the breaker means disconnects the source the reverse voltage from said primary is applied to said meter through a maximum resistance.

6. Means for measuring the dwell of the periodic breaker means of an ignition circuit having a source of current and an induction coil primary in series with said breaker means, comprising a current-responsive measuring device connected across an element in said circuit, and a rectifier in series with said measuring device, the rectifier having such a polarity that when current flows through said circuit from said source it is applied to said measuring device through minimum resistance, but when the breaker means disconnects the source of current, the reverse voltage through said circuit is applied to said measuring device through a maximum resistance.

7. Means for measuring the dwell of the periodic breaker means of an ignition system having a source of current, an induction coil primary, and breaker means connected in series, said means comprising a main circuit connected in parallel with an impedance in said ignition system, said main circuit including a current-responsive device and an impedance in series, and a second circuit shunted across said main circuit and including an impedance, the impedance of said second circuit being so arranged that said second circuit offers a path of substantially lower impedance to the flow of the current than said main circuit when said breaker means are open.

BENJAMIN C. LANSDALE.
